Primary Examiner — Holly Baynham(74) *Attorney, Agent, or Firm* — Andrew F. Young, Esq.;
Lackenberg Siegel, LLP(57) **CLAIM**

The ornamental design for a frame folio sleeve, as shown and described.

DESCRIPTION

FIG. 1 is a front perspective view of the present invention.

FIG. 2 is a front elevation view of FIG. 1.

FIG. 3 is a rear elevation view of FIG. 1.

FIG. 4 is a top plan view of FIG. 1.

FIG. 5 is a bottom plan view of FIG. 1.

FIG. 6 is a left side elevation view of FIG. 1; and,

FIG. 7 is a right side elevation view of FIG. 1.

The broken lines showing the handbag sides, zipper, piping and handles are for the purposes of illustrating environment and form no part of the claimed design.

UNITED STATES PATENT AND TRADEMARK OFFICE
CERTIFICATE OF CORRECTION

PATENT NO. : D652,214 S
APPLICATION NO. : 29/381880
DATED : January 17, 2012
INVENTOR(S) : Swartz et al.

Page 1 of 1

It is certified that error appears in the above-identified patent and that said Letters Patent is hereby corrected as shown below:

Title Page; in the Description, the following correction is made:

On line 9, the word "and handles" should be removed.

Signed and Sealed this
Third Day of April, 2012

David J. Kappos
Director of the United States Patent and Trademark Office
